UNITED STATES PATENT OFFICE.

FREDERICK TASKER BURGESS, OF LONDON, ENGLAND.

PISTON FOR FLUID-PRESSURE ENGINES.

Application filed July 27, 1923. Serial No. 654,254.

To all whom it may concern:

Be it known that I, FREDERICK TASKER BURGESS, a subject of the King of England, residing at London, England, have invented 5 certain new and useful Improvements in Pistons for Fluid-Pressure Engines, of which the following is a specification.

This invention relates to pistons for fluid pressure engines, and it has for its principal 10 object to provide a construction which will have but small clearance at the skirt and thus will avoid piston slap, and also ensure an effective scraper action on the cylinder walls. A further object is to minimize 15 transfer of heat from the head to the skirt.

In the accompanying drawings,

Figure 1 is a central vertical section, and Figure 2 a horizontal section on the line 2—2 of Figure 1, illustrating one construction. 20

Figure 3 is a central vertical section, and Figure 4 a horizontal section on the line 4—4 of Figure 3, illustrating an alternative construction.

Like letters indicate like parts throughout the drawings.

In the construction shown in Figures 1 and 2, the web portion is in the form of a hollow neck A of relatively small diameter 30 where it unites with the crown B, but, with an easy sweep therefrom, it increases in diameter to unite with the skirt portion C, serving at the junction to stiffen the piston pin bosses D thereon, and preferably meeting 35 the skirt at or near the level of the piston pin axis. In this way an annular channel E is formed between the neck and the adjacent edge of the skirt, and this edge is so formed as to have a scraping action 40 which collects into the channel excess lubricant from the walls of the cylinder. Perforations F may be provided on the side or base of the channel to allow the collected lubricant to pass to the working faces of the 45 piston pin, and also to drain back to the sump.

The skirt of the piston is slit from end to end, in this case at two places G and H opposite one another and between the piston pin bosses. These slits extend into the neck A, terminating in circular holes J drilled or cored in the neck at a point between the crown and the skirt. Thus the web A is divided into two parts and resilience is imparted to the opposite sides C² and C³ of 55 the skirt which carry the bosses D, not mere-

ly for a part of its length but for the whole thereof, ensuring close contact with the cylinder walls and an avoidance of piston slap without risk of binding or seizing. 60

If desired the skirt may be provided at the end remote from the crown with an internally arranged spring ring K adapted to expand the split parts, in which case the skirt would preferably be sized initially 65 for an exact working fit in the cylinder. Any other suitable means of causing the skirt to tend to expand may be used.

Also each end of the skirt may have a bevelled edge C⁴ and C⁵ so that a scraping 70 action takes place both on instroke and outstroke of the piston.

The neck web portion A is made of small diameter and with thin sides and thus the passage of heat from the head to the skirt 75 is minimized.

In the construction shown in Figures 3 and 4, the design is substantially the same, but the web portion, instead of being originally of circular or similar continuous 80 shape, is divided into two separate webs A² and A³ each of which unites with one skirt part. Thus the web A² unites with the skirt part C² and the web A³ with the skirt part C³. If desired, each web portion A² 85 or A³ may be divided vertically into two parts one lying on each side of the gudgeon pin boss F. The web portions A² and A³ may be curved as shown, or may be flat. According to the sectional shape the desired 90 stiffness of the webs can be obtained, as it will be clear that where the webs are of curved section they are stiffer than where they are of flat formation.

Preferably in each case the webs A² and 95 A³ incline towards one another at the top, so that when the piston is under load the tendency is for the skirt parts C² and C³ to spread and to work closely in the cylinder bore.

Although it has been stated that the skirt parts in both constructions are separated from one another, as by the slits H, in some designs, where the piston pin bosses F are low down, it might not be essential that the 105 skirt portion should be slit from end to end; and I wish to make it clear that my invention covers constructions in which the skirt is split substantially from end to end so that the desired separating effect of the 110 skirt side can be obtained.

Again, in some cases the skirt may be

split at a single point between the piston pin bosses, the skirt being still free to expand and the bosses to move towards and away from one another, as will be readily understood.

In the construction shown in Figures 3 and 4 the skirt is formed with a number of grooves C^6 and oil holes C^7 whilst the edges C^8 and C^9 are so bevelled as to encourage the oil to flow along the skirt and pass away to the interior through the grooves C^6 and holes C^7 .

In manufacturing a piston of this kind in aluminium alloy, the skirt can be machined cylindrical to the exact bore of the cylinder, or with only a very small running clearance, such as is used with pistons having cast iron skirts. If the fit is too tight the skirt will contract slightly, but if too loose it will expand, and, during the firing stroke, and probably also during the compression stroke, when the loads are highest, the pressure on the crown causes the lower ends of the webs to tend to spread, so that any clearance is taken up and the skirt fits the cylinder the whole way round, ensuring distribution of the wear and absence of noise. In addition, it will be clear that there can be no slap or noise of the piston in the cylinder walls and that, in spite of the close fit, seizure of the piston is prevented owing to its ability to yield inwards. Again, distortion of the skirt in the neighbourhood of the piston bosses is reduced to a minimum, and as the webs can be thin the amount of heat conducted from the crown is very small.

It will be understood that the complete piston is usually cast in one but any suitable built-up construction may be adopted.

Furthermore, pistons of a standard size

will fit worn or "over-size" cylinders, which is a great saving in repair work.

What I claim as my invention and desire to secure by Letters Patent of the United States is:—

1. In a piston, in combination, a crown, a separate expansible skirt having bosses for the piston pin, inclined webs connecting the crown and the skirt in such a manner that pressure on the crown causes expansion of the skirt.

2. In a piston, in combination, a crown, a separate skirt divided into two parts by longitudinal slits, a piston pin boss in each part, a web portion connecting each part of the skirt to the underside of the crown, uniting with the skirt parts close to the piston pin bosses and forming the sole connection between the crown and skirt.

3. In a piston, in combination, a crown, a separate two part skirt, a piston pin boss in each part, an inclined web portion connecting each part of the skirt to the underside of the crown and forming the sole connection between said parts.

4. In a piston, in combination, a crown, a separate expansible skirt having bosses for the piston pin, inclined curved webs connecting the crown and the skirt in such a manner that pressure on the crown causes expansion of the skirt.

5. In a piston, in combination, a crown, a separate skirt divided into two parts by longitudinal slits, a piston pin boss in each part, a curved web portion connecting each part of the skirt to the underside of the crown, uniting with the skirt parts close to the piston pin bosses and forming the sole connection between the crown and skirt.

In testimony whereof I affix my signature.

FREDERICK TASKER BURGESS.
